(57) **CLAIM**

The ornamental design for a set of electric candle and base as shown and described.

DESCRIPTION

FIG. 1 is a perspective view of a set of electric candle and base showing my new design;

FIG. 2 is a perspective view of a base of the set of electric candle and base, shown separately for ease of illustration;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a perspective view of an electric candle of the set of electric candle and base, shown separately for ease of illustration;

FIG. 11 is another perspective view thereof;

FIG. 12 is a front elevational view thereof;

FIG. 13 is a rear elevational view thereof;

FIG. 14 is a left side elevational view thereof;

FIG. 15 is a right side elevational view thereof;

FIG. 16 is a top plan view thereof; and,

FIG. 17 is a bottom plan view thereof.

The base is shown with symbolic breaks in its length and the appearance of any portion of the base between the break lines form no part of the claimed design. The broken lines in the drawings depict portions of the set of electric candle and base that form no part of the claimed design.

1 Claim, 17 Drawing Sheets
